UNITED STATES PATENT OFFICE

HUGO A. MAASHOFF, WALTER C. GREIST, AND ANDREW J. CARMICHAEL, OF NEW HAVEN, CONNECTICUT, ASSIGNEES TO THE GREIST MANUFACTURING COMPANY, A CORPORATION OF CONNECTICUT

SEWING-MACHINE RUFFLER

Application filed March 26, 1928. Serial No. 264,846.

This invention relates to that class of sewing machine rufflers generally known as "five-stitch" rufflers in that they may be adjusted so as to effect a reciprocating movement of the ruffling blade at each five stitches of a sewing machine, when it is desired to make wide ruffles or plaits, or may be so adjusted as to make a narrow ruffle or gather at each stitch of the sewing machine; or, if plain sewing is to be done, may be thrown out of action without being removed from the sewing machine. The present invention has for its object to widen the range of work to be performed by rufflers of the class referred to so that the ruffler may be adjusted so as to make a ruffle or gather at each stitch of the sewing machine, or at each five or ten or any other desired number of stitches; or may be thrown out of action when plain sewing is to be done. The present invention is an improvement on that class of sewing machine rufflers shown by U. S. Patents Nos. 1,261,628 and 1,392,970.

The present invention also provides means whereby a wider ruffle may be made than is possible by the use of rufflers of the class referred to, all as will be hereinafter fully set forth.

In the accompanying drawing Figs. 1 and 2 are opposite side views of the improved ruffler. Fig. 3 is a rear end view and Fig. 4 a plan view of the same. Figs. 5 and 6 are detail views of the ratchet wheels. Figs. 7 and 8 are detail views to show more clearly certain parts shown in Figs. 2 and 3.

Figs. 9 and 10 are detail views to show more clearly the adjustable lever 25 on the arm 14^b of the pendulous lever 14.

Referring to the drawing, 12 denotes the frame of the ruffler constructed for attachment to the presser foot of a sewing machine, 13 the operating lever, 14 the pendulous lever, 15 the ruffling blade carrier having a pivotal connection with the lower end of said pendulous lever, 17 the ruffling blade, 13^c the adjustable contact screw, and 16 the separator plate, these parts being, excepting for the attachment to an arm, to be referred to, on said pendulous lever, substantially the same as in the patents referred to above.

Mounted on a stud 18, which serves as a ful-

crum pin for the operating and pendulous levers, are two ratchet wheels 19 and 20, the ratchet wheel 19 having a series of shallow notches 21, affording short radial teeth, and two deep notches 22 between the shallow notches. The ratchet wheel 20 is provided with a single deep notch 22 and with eleven shallow notches. The said ratchet wheels are spaced apart from each other but are connected so as to rotate together and the deep notch of the ratchet wheel 20 registers with one of the deep notches in the ratchet wheel 19.

Pivottally attached to a laterally extending lug 13^a, at the top of the operating lever 13, 65 is a yieldingly mounted plate 23; and, integral with said plate, is a downwardly extending pawl 24. Owing to its pivotal connection with the lug 13^a the free end of the said plate 23 is adapted to be adjusted laterally so as to 70 bring any one of the openings 23^a, 23^b, 23^c and 23^d, near the free end of said plate, into register with an upwardly projecting finger 13^b on the said operating lever. A similar adjustable pawl-carrying plate is shown in Patent No. 1,392,970, and also in Patent No. 1,261,628.

The pendulous lever 14 is provided, as in the construction shown in the patents above referred to, with a shoulder 14^a; and by adjusting the pawl-carrying plate 23 so that the finger 13^b will extend through the opening 23^c, the pawl 24 will be adjusted laterally so that it will be out of register with the ratchet wheels 19 and 20, but will be in register with the said shoulder 14^a, and will thus cause a reciprocating movement to be imparted to the ruffling blade 17 at each stitch of the sewing machine.

If, however, the said plate 23 be adjusted to bring the opening 23^b into register with said finger 13^b the pawl 24 will be brought into register with the ratchet wheel 19, having two deep notches, and the short radial teeth afforded by the shallow notches will serve to hold said pawl above the said shoulder 14^a; but when, in the rotation of the said ratchet wheel, one of the deep notches comes beneath said pawl the latter will drop down far enough to engage the said shoulder 100

14^a on the pendulous lever and a forward movement of the ruffling blade will then be effected. Thus with the adjustment just referred to a ruffle or gather will be formed at each six stitches of the sewing machine when the movements of the ruffling blade are controlled by the ratchet wheel 19.

If, however, the said plate 23 be adjusted so as to bring the opening 23^c into register with the said finger 13^b the pawl 24 will be held above the said shoulder 14^a excepting when the single deep notch in the ratchet wheel 20 is reached; and thus the movement of the said ruffling blade will be effected only 15 at each twelve stitches of the sewing machine when the movements of the ruffling blade are controlled by the ratchet wheel 20. When, however, the plate 23 is adjusted to bring the small opening 23^d into register with the finger 13^b the plate 23 will be lifted high enough so that the pawl 24 will be entirely clear of both ratchet wheels, as indicated by dotted lines in Fig. 2; so that no movement at all will be imparted to the ruffling blade, and thus plain 20 sewing may be effected. It will be noted that the rounded upper end of the finger 13^b is adapted to enter but not pass through said opening 23^d, so that the plate 23 will be supported by said finger and will be held in the 25 raised position denoted by the dotted lines referred to.

From the foregoing it will be understood that the range of the work of the class of rufflers to which the invention relates is widened by permitting a ruffle to be made at each 30 stitch, at each six stitches, and also at each twelve stitches, instead of only at each stitch and at each five stitches, as in the rufflers of the patents hereinbefore referred to.

Attached to the contact arm 14^b on the pendulous lever 14 is a small lever 25 which may be adjusted so that its upper inturned end 25^a comes beneath the adjustable contact screw 13^c carried by the operating lever 13, so as to practically increase the working 40 length of said arm and thus diminish the lost motion between said screw and the said pendulous lever (without adjusting said screw) to such an extent that, with a proper adjustment of the said contact screw, there will be little or no lost motion between the operating lever and the pendulous lever; and thus by the quick adjustment of said lever, a very 45 long stroke will be imparted to the said pendulous lever and to the ruffling blade connected therewith so as to make very wide ruffles when desired. For ordinary work, however, the said contact lever will be adjusted to the 50 inoperative position shown in full lines in Fig. 1, and when thrown into operation will assume the position shown in dotted lines in Fig. 1, and in full lines in Figs. 9 and 10.

To prevent backward movement of the ratchet wheels when the operating lever is 55 moved upward, a spring detent pawl 26 is at-

tached to the frame 12 and is provided with a laterally extending finger 27 which engages the teeth of the ratchet wheel 20 and thus positively prevents backward movement of said ratchet wheels when the needle bar, from which the operating lever is actuated, is performing a downward movement.

Beneath the pivoted end of the pawl-carrying plate 23, and interposed between the operating lever and said plate, is a volute or helical coil spring 28 which permits a proper yielding action of said plate as the pawl 24 rides over the teeth of the ratchet wheel or wheels. Heretofore plain or cylindrical coil springs and plate springs have been used in this connection, but experiments have demonstrated that said volute spring enables the ruffler to work much better than the said previous springs, said volute spring affording a wider bearing against said pawl-carrying plate than the springs previously employed.

It will be understood that the construction of the ratchet wheels 19 and 20 may be varied so as to provide a greater or lesser number of the deep and shallow notches than those shown in the drawing so that the ruffling blade will be operated to make a ruffle or gather at each five or ten, or any other desired number of the stitches of the sewing machine, instead of at each six or twelve 95 stitches as will result with the particular construction of ratchet wheels shown in the drawing.

Having thus described our invention, we claim and desire to secure by Letters Patent: 100

1. In a sewing machine ruffler, the combination with an operating lever, of a pawl connected therewith to be actuated therefrom, a plurality of connected ratchet wheels having shallow and deep notches, means for adjusting said pawl laterally so that it may engage either of said wheels or may be displaced from either of them, a pendulous lever having a shoulder to be engaged by said pawl, and a ruffling blade operatively connected with said pendulous lever.

2. In a sewing machine ruffler, the combination with an operating lever, of a pawl connected therewith to be actuated therefrom, two connected ratchet wheels having shallow and deep notches, means for adjusting said pawl laterally so that it may engage either of said wheels or may be displaced from either of them, a pendulous lever having a shoulder to be engaged by said pawl, and a ruffling blade operatively connected with said pendulous lever, one of said ratchet wheels having a single deep notch and the other having a plurality of deep notches.

3. In a sewing machine ruffler, the combination with an operating lever and a contact screw mounted thereon, of a pawl operated from said lever, a pendulous lever having a shoulder to be engaged by said pawl and having an arm to be engaged by said screw, a

lever mounted on said arm and positioned so that its free end may be brought beneath said screw to increase the working length of said arm, and a ruffling blade operatively connected with said pendulous lever; whereby, when desired, the lost motion between said screw and said arm may be lessened to increase the throw of said ruffling blade without adjusting said screw.

4. In a sewing machine ruffler, the combination with an operating lever and a frame or support on which said lever is mounted, of a pawl connected therewith to be actuated therefrom, two connected ratchet wheels both having deep and shallow notches to be operated by said pawl, a spring detent pawl mounted on said frame or support and serving to prevent backward movement of said wheels, a pendulous lever having a shoulder to be engaged by said pawl, and a ruffling blade operatively connected with said pendulous lever.

In testimony whereof we affix our signatures.

HUGO A. MAASHOFF.
